TRAIN ORDER DELIVERER

Bernard V. Robbins, Cayuga, Ind.

Application July 18, 1939, Serial No. 285,142

2 Claims. (Cl. 258—2)

The invention relates to improvements in apparatus for delivering train orders to fast moving trains from station platforms, or the like.

The invention is designed with the particular purpose in view of providing apparatus of the character specified for delivering such orders in duplicate copy, one at the head end of the train, and the other at the tail end thereof, for the engineer and conductor, respectively, and automatically with perfect safety to the engineer and conductor and others concerned.

Another object in view is to provide apparatus for the purpose above specified adapted for duplicating delivery of duplicate order copy, as, for instance, to a double-header train, or in other words, one running with two engines and cabooses, one caboose behind the second engine.

Still another object is to simplify such apparatus especially by way of eliminating, as operating parts, all springs, and to utilize in lieu thereof gravity-operated parts.

To the accomplishment of the above, and subordinate objects presently appearing, a preferred embodiment of my invention has been illustrated in the accompanying drawings, set forth in detail in the succeeding description and defined in the claims appended hereto.

In said drawings:

Figure 1 is a view in side elevation of the preferred embodiment of my invention with the parts shown in normal position.

Figure 2 is a view in top plan,

Figure 3 is a detailed view in perspective of one of the fork carriers, and

Figure 4 is a fragmentary view in top plan of the receiving device.

Referring to the drawings by numerals, the illustrated embodiment of my invention comprehends, as a basic element thereof, a tubular, preferably metal post 1 adapted to be mounted along side the track, as for instance, on a platform 2 and by means of a support 3 comprising a base plate 4 bolted to the platform, as at 5, and having upstanding therefrom a tubular socket 6 in which the lower end of the post 1 is fitted for rotation of the post therein into different set positions as established by a set screw 7 threaded into said socket 6 and extending into a circumferential quadrant slot 8 provided in said post.

Extending laterally from the post 1, to one and the same side thereof, is a pair of tubular arms 9 disposed parallel in superposed relation and having rear ends fixed to the post 1 by means of T-shaped sleeves 10 riveted to said post as at 11. The arms 10 support, at the outer ends there-

of, a pair of upper and lower order holding units 12, 13, respectively, adapted to be revolved in unison into and out of a position intermediate said post and a passing train under rotation of the post 1 through a quarter turn in opposite directions, respectively, such intermediate position being the delivery positions of the holding units as will be understood, and the set screw 7 and slot 8 establishing the opposite limits of said quarter turn.

The holding units 12, 13 are counterparts, each of the other so that a description of one will suffice for both.

The primary element of the holding units 12, 13 is a block-like, flat fork carrier 14 of suitable metal comprising a pair of right-angularly related branches 15. The carrier 14 is mounted, as presently described, at the outer end of its related arm 9 for vertical swinging movement in a vertical plane coincident with the axis of said arm from normal into inverted positions, respectively, and vice versa. In the normal position of the carrier 14, the branches 15 extend upwardly and forwardly relative to the arm 9, respectively, whereas, in the inverted position of said carrier, said branches extend downwardly and forwardly, respectively.

The mounting for the carrier 14 comprises a substantially U-shaped bearing yoke 16 mounted at the front end of the related arm 9 to extend forwardly therefrom and by means of a shank part 17 riveted, as at 18, to said arm. A pivot pin 19 extending through said yoke 16 and the corner of the carrier 14 formed by the juncture of the branches 15 secures said carrier in said yoke, the arrangement being such that the edges of the carrier coat with the rear end of the yoke to establish the normal and inverted positions of said carrier.

Pairs of order-retainers 20 are mounted, as presently described, at the ends of the branches 15, respectively, to extend outwardly from said ends, each retainer comprising a V-shaped base block 21, of suitable wood, and a pair of outwardly divergent slats 23 secured to the side edges of said block as at 24. The blocks 21 are secured to the branches 15 so that the slats 23 are disposed in the plane of the carrier 14. In the case of the normally upwardly extending branches 15 the block 21 is secured thereto by means of a clip 25 riveted, as at 26, to said branches to project laterally therefrom in the plane of the carrier 14, the block 21 being provided with a shank 22 detachably fitted in said clip 25 and releasably retained therein by means

of a spring-pressed bolt 27 suitably mounted in the branch 15. In the case of the normally forwardly extending branch 15, the blocks 21 are secured in any suitable manner directly to the branch. The outer ends of the slats 23 are bifurcated, as represented at 28, and each block 21 has fixed to one side thereof, as at 29, a spring clip 30. An endless band 31 of resilient cord, or the like, is trained through the bifurcated ends 28 of each pair of slats 23 and through the clip 30 of the related blocks 21. The train orders, not shown, are attached to the bands 31 in any manner desired. As will now be understood, each order holding unit 12, 13, includes a pair of order retainers 20, one normally upstanding and the other normally outstanding toward a passing train, said retainers being mounted in substantially right-angled 90° angular relation for vertical swinging movement about a common axis 19 and under the influence of gravity so that the outstanding retainer may drop into a pendant position and the upstanding retainer assume the outstanding position. As will also be apparent, each order retainer 20 is equipped with detachable means, in the form of the band 31, for securing an order copy thereto, which means in the outstanding position of the retainers may be easily detached together with the order copy by a pull exerted from a passing train on the section of the band trained through the bifurcated ends 28 of the retainer.

Associated with each order-holding unit 12, 13 is latching mechanism for retaining the carrier 14 in normal position and hence the order retainers 20 in upstanding and outstanding positions, respectively.

The latching mechanism in each instance comprises the following: The carrier 14 is provided with a notched latch dog 32 pivoted to one side of the normally upstanding branch 15, as at 33, for swinging movement in opposite directions into latching and unlatching positions, respectively, relative to a lug 35 on the yoke 16. A coil spring 36 suitably connected to said dog and carrier urges the dog toward unlatching position. A lever-like dog trip 37 is pivoted, as at 38, on the carrier 14 for rocking movement of one end thereof into engagement with said dog so as to block rocking of the latter from latching position. A trip rocking rod 39 is pivoted at one end, as at 40, to the other end of said trip, said rod being mounted intermediate its ends on the normally outwardly extending branch 15 for endwise movement to unlock said trip, the mounting comprising a link 42 pivoted to said rod 39 and to a lug 43 on said branch, as at 44, 45, respectively. The rod 39 is designed to be held against endwise movement by detent means as follows: Rotatably mounted in the normally outwardly extending block 21 is a detent rod 46 having a bearing in a sleeve 41. One end of the rod 46 is hook-shaped, as at 49, for cooperation with an angularly related end 50 of the rod 39 to hold the latter stationary and adapted under rotation of the rod 46 in one direction to release said end 50. The other end of the rod 46 has a crank part 51 adapted to extend across the appropriate band 31 so that when said band is detached the crank part will be rotated thereby to rotate said hooked end 49 into releasing position relative to said end 50 of rod 39. Obviously, when said rod 39 is released, the spring 36 will swing the dog 32 to unlatching position and under the influence of gravity the order holding units 12, 13 will revolve so that outstanding

order retainer 20 will drop and the upstanding retainer 20 will take its place.

Referring to the operation of the apparatus as so far described, with the parts in the normal position described, detachment of the band 31 of the forwardly extended order retainer 20 of either the upper or lower order holding units 12, 13, will cause rotation of the detent rod 46 of the units to release the locking rod 39 of the trip 37 whereupon the latch dog 32 will be swung by its spring 36 to unlatching position thereby conditioning the units from which the band is detached for gravitational action to revolve the forwardly extending order retainer downwardly out of delivering position and the upwardly extending order retainer 20 into its place or in other words into delivering position. Therefore, as will be clearly seen, one order copy may be taken from the normally forwardly extending order retainer 20 and another from the other order retainer subsequently. Either order holding unit 12, 13, may be utilized first for presenting duplicate order copy for successive delivery. The manner in which the order holding units 12, 13 may be revolved back to normal position and latched in such position will, it is believed, be clearly understood without explanation. When the apparatus is not in use, the order holding units 12, 13 may be revolved into an out-of-the-way position in a manner which will be understood from the foregoing description. In order that the order holding units 12, 13 may be arranged in closely spaced superposed relation, the arms 9 may be bent laterally in opposite directions as illustrated in Figure 2, so that said units are staggered to prevent interference of the upper units with the lower in operation thereof.

For detaching the bands 31 the receiving device illustrated in Figure 4 may be provided on the engine and caboose as the case may be. Said device comprises an arm 52 pivoted at one end, as at 53, to a bearing bracket 54 adapted to be bolted, as at 55, to the side of the engine or caboose so that said arm may be extended outwardly from the latter or swung inwardly alongside the same as shown in dotted line. The bracket 54 has suitably attached thereto a spring clip device 56 for engagement with said arm 52 to yieldingly retain the same in inwardly swung position. A suitable stop pin 57 is provided on the bracket 54 for engagement with the arm 52 to limit outward swinging of the same. The outer end of the arm 52 is equipped with a V-shaped grab hook 58 of any suitable resilient metal adapted under movement of the train to span the stretch of the band 31 trained through the bifurcated ends 28 of the order retainer 20 and thereby detach the same in a manner which will be clear. The arm 52 and hook 58 are provided with a pair of opposed resilient keeper fingers 59 extending across the hook with a gap 59 therebetween so that the band 31 may enter the hook but be prevented by said fingers from jumping out of the same.

The foregoing will, it is believed, suffice to impart a clear understanding of my invention without further explanation.

Manifestly the invention, as described, is susceptible of modification without departing from the inventive concept and right is herein reserved to such modifications as fall within the scope of the subjoined claims.

What I claim is:

1. Apparatus for delivering train orders comprising a post, an arm fixed to and extending

laterally from said post, a pair of train order holders at the outer end of said arm spaced apart in 90° angular relation and each including a pair of outwardly divergent bars, means to mount said holders on the outer end of said arm for gravitational swinging movement in a vertical plane from a normal position and including a carrier pivoted on said arm, said pair of holders in said normal position extending forwardly of said arm and upwardly therefrom, respectively, a pair of order holding loops one detachably attached to each of said holders and held open by said bars, latch mechanism pivoted on said carrier coacting with said arm for retaining said holders in normal position and constructed and arranged to be tripped for unlatching operation, and means to trip said mechanism comprising a rotary crank shaft on one of said order holders having a crank disposed within the loop on said holder for operation by the latter as an incident to detachment of said loop.

2. Apparatus for delivering train orders comprising a post, an arm fixed to and extending laterally from said post, a pair of train order holders at the outer end of said arm spaced

5 apart in 90° angular relation and each including a pair of outwardly divergent bars, means to mount said holders on the outer end of said arm for gravitational swinging movement in a vertical plane from a normal position and including a carrier pivoted on said arm, said pair of holders in said normal position extending forwardly of said arm and upwardly therefrom, respectively, a pair of order holding loops one detachably attached to each of said holders and held open by said bars, latch mechanism pivoted on said carrier coacting with said arm for retaining said holders in normal position comprising a dog, a latching dog spring tensioned toward unlatching position, trip mechanism for holding said dog in latching position including a tripping lever, and means to lock said lever in holding position comprising a crank shaft rotatably mounted on one of said order holders for operation into and out of locking position relative to said lever and having an operating crank swingable into the loop on said holder for operation by said loop as an incident to detachment of the same.

BERNARD V. ROBBINS.
